Pines Law Group, PC

(57) **CLAIM**

The ornamental design for a standing bird feeder, as shown.

DESCRIPTION

FIG. 1 is a side perspective view of a standing bird feeder showing my new design;

FIG. 2 is a first side elevational view of the standing bird feeder;

FIG. 3 is a second side elevational view of the standing bird feeder;

FIG. 4 is a third side elevational view of the standing bird feeder;

FIG. 5 is a top plan view of the standing bird feeder; and,
FIG. 6 is a bottom plan view of the standing bird feeder.

1 Claim, 5 Drawing Sheets
